UNITED STATES PATENT OFFICE.

WILLIAM E. SLOAN, OF CHICAGO, ILLINOIS.

CLOSET-SEAT DEVICE.

1,339,585.

Specification of Letters Patent. Patented May 11, 1920.

Application filed March 17, 1913. Serial No. 754,722.

To all whom it may concern:

Be it known that I, WILLIAM E. SLOAN, a citizen of the United States, residing at Chicago, in the county of Cook and State 5 of Illinois, have invented a certain new and useful Improvement in Closet-Seat Devices, of which the following is a specification.

This invention relates to improvements in 10 closet seat devices, and has for its object to provide a new and improved device of this description. The invention is illustrated in the accompanying drawings wherein—

Figure 1 is a view showing one form of 15 device embodying the invention;

Fig. 2 is an enlarged sectional view through the portion of the flush valve showing the operating mechanism;

Fig. 3 is a view similar to Fig. 2 with the 20 parts in a different position;

Fig. 4 is a plan view;

Fig. 5 is an enlarged view in part section showing a portion of the connection between the seat and the flush valve;

Fig. 6 is a sectional view taken on line 25 6—6 of Fig. 7;

Fig. 7 is a sectional view taken on line 7—7 of Fig. 6.

Like numerals refer to like parts through- 30 out the several figures.

Referring now to the drawings, I have shown a device consisting of a bowl 1 with a seat 2 having a hinged connection. This seat is provided with a bracket 3 having 35 projections 4 connected with the cross piece 5. The seat is therefore moved about the cross piece as an axis. Some means is provided for limiting the upward movement of said seat. As herein shown the projec- 40 tions 4 are provided with ingaging faces 4^a which engage stops 5^a on the supports 5^b for the cross piece 5, the parts being ar- ranged so that when the seat is lifted to a predetermined position, its further move- 45 ment is stopped. Mounted upon said cross piece is a movable part 6 provided with an adjustable piece 7 adapted to engage some part connected with the seat 2, as for example, a portion of the bracket 3. Between 50 the part 6 and the projections 4 are the spacing pieces or sleeves 6^a. Adjustably mounted upon the part 6 is a rigid connecting piece 7, which may be held in any desired position by means of the set screw 55 8^a. Connected with the piece 7 is a flexible piece 8 which leads to the flush valve 9.

This flexible piece is adjustably connected with the piece 7 in any desirable manner as by means of the set screw 10. The flush valve is connected with the bowl so as to 60 flush it. The flexible piece 8 is fastened at the other end to a movable piece 11 (see Figs. 2 and 3). This movable piece is pro- vided with a projecting end 12 adapted to engage the actuating stem of the flush valve. 65 This flush valve is illustrated as of the type shown in my Patent No. 1,114,398, filed June 2, 1909, issued October 20, 1914, which is made to flush by tilting the actuating stem of the valve to one side. When this actu- 70 ating stem is moved to one side the valve and stem are lifted by the water as illustrated in my prior application and patent. This actuating stem consists of two parts or members, a member 13 and a sliding mem- 75 ber 14 associated therewith, said actuating stem being actuated by being moved to one side as shown in dotted lines in Fig. 2. The piece 11 is movably mounted in the piece 15 associated with the flush valve which con- 80 tains the retracting spring 16 which engages the piece 11 so as to normally hold it in the position as shown in Fig. 2. This construc- 85 tion gives a much greater range of adjustment and adaptability. When the flush valve is mounted directly upon the bowl as shown in Fig. 1, it is found in practice that the holes for the seat post of the hinge and the hole for the flush valve are separated at varying distances in different makes of 90 bowls and very often in the same make of bowl, and hence some adjustable means must be provided for connecting the hinge with the operating part of the flush valve so as to adapt the device to these varying 95 conditions. These distances also vary on the different jobs when the flush valve is installed separate from the bowl instead of being mounted thereon. With the devices heretofore used, the adjustment was so lim- 100 ited as to make it difficult to secure a proper connection between the hinge and the oper- ating portion of the valve. In the present construction, this is obviated because the flexible part permits of a greater range of 105 adjustment both in length and laterally be- cause it is free to be moved laterally to make connections when the parts are out of aline- 110 ment. The flexible part 8 is preferably a wire cable so that it will not easily deteriorate and is sent out separately from the part 7, being preferably connected with the flush

valve. When the parts are assembled, the end of the flexible part 8 is then inserted in the opening of the part 7 and the parts moved relatively to get the proper adjustment and the set screw 10 then tightened. Further adjustment is also secured by the set screw 8^a and by the adjustable part 7^a. When the parts are connected in position, the spring 16 holds the seat partially lifted as shown in Fig. 1. When the seat is pushed down, the parts are moved so that the flexible part 8 pulls on the movable part 11 and moves it to the position shown in Fig. 3, thus moving the part 12 from beneath the part 14 and allowing said part to slide down to the position shown in Fig. 3. When the seat is released, the spring 16 of the flush valve moves the part 11 back to its initial position. This causes the part 12 to engage the part 14 and move it sidewise to the position shown in dotted lines in Fig. 2, thus actuating the flush valve and causing the valve and the parts 13 and 14 to be lifted as described in my Patent No. 1,114,398, issued October 20, 1914, and causing the bowl to be flushed. The part 14 is moved by the spring 16 so as to be under the part 12 and when the main valve seats again as described in my said prior patent, the part 14 comes down upon the part 12 as shown in Fig. 2. It will thus be seen that the bowl is flushed not when the seat is pushed down but when it is lifted. It will further be seen that the spring 16 which controls the flush valve actuating part 12 also lifts the seat to its normal or lifted position. By means of this construction, I am enabled to produce a cheap, efficient device which can be readily adjusted to meet the varying conditions presented in practice. It will further be noted that in this construction the flush valve is operated by means of a pull forward instead of by pushing force tending to move it backward. I have found in practice that this is a considerable advantage in preventing injury and displacement of the parts.

The flexible part 8 may be soldered to the part 11 or may be fastened thereto in any other desired manner.

I claim:

1. A closet seat device comprising a seat, a flush valve associated with said seat, an actuating stem for the flush valve connected therewith so as to be lifted thereby when the flush valve is operated and consisting of two members, one a sliding member sliding on the other, the flush valve being operated by moving said actuating stem later-

ally, a reciprocating part for operating said actuating stem, said reciprocating part normally projecting under said sliding member and supporting it, a connection between said seat and said reciprocating part, said connection consisting of a rigid pivotal part 65 engaged by the seat so as to be moved thereby, a flexible part connecting the rigid pivotal part and the reciprocating part, whereby when the seat is pressed down said reciprocating part is moved from under the sliding member so as to permit it to slide downwardly, and a retracting spring for retracting said reciprocating part when the seat is released, so as to cause the reciprocating part to strike said sliding member and move 75 the valve actuating stem laterally to operate the flush valve.

2. A closet seat device comprising a seat, a flush valve associated with said seat, a reciprocating part for operating said flush 80 valve, a connection between said seat and said reciprocating part comprising a flexible part, a rigid part to which the flexible part is adjustably connected and having an opening therein and a pivoted part to which said 85 rigid part is adjustably connected, said flexible part having a portion which is substantially horizontal and a portion which is substantially vertical, said latter portion extending into the opening in said rigid part. 90

3. A closet seat device comprising a seat, a flush valve adapted to be controlled by said seat, a reciprocating part for operating said flush valve, a hinge for said seat, an operating connection between said hinge 95 and said reciprocating part, comprising a rigid section having two adjustable parts one connected with said hinge so as to be moved thereby, the other having an adjustable sliding connection with the first mentioned part, said latter part provided with a longitudinal opening, a flexible piece extending into said longitudinal opening, means for adjustably holding the flexible piece in said opening, said flexible piece being bent after leaving said opening, the bent 105 portion being substantially horizontal, and a connection between said bent portion and the reciprocating part for operating the flush valve.

In testimony whereof I affix my signature in the presence of two witnesses this 14th day of March, 1913.

WILLIAM E. SLOAN.
